FIG.1

FIG.2

FIG.3

FIG.4

FIG. 1 is a top perspective view of a gas laser embodying our design;

FIG. 2 is a top plan view of the laser of FIG. 1;

FIG. 3 is a side elevational view of the laser of FIG. 1, the reverse side being substantially identical in appearance; and

FIG. 4 is a left end view of the laser of FIG. 1, the opposite end being substantially identical in appearance except for the lack of an aperture.

The dominant features of my design reside in the portions shown in full lines and set off.

We claim:

The ornamental design for a gas laser, as shown and described.
